VENTILATOR FOR SILOS, CRIBS, OR THE
LIKEFrank H. Anderson, Des Moines, Iowa, assignor to
New Monarch Machine & Stamping Co., Des
Moines, Iowa

Application September 18, 1939, Serial No. 295,447

2 Claims. (Cl. 98—54)

The principal object of this invention is to provide a ventilator for silos, cribs, or the like which may be incorporated in ordinary silo construction in conjunction with other types of materials, such as concrete slabs, or the like for thoroughly ventilating the ensilage, grain, or other contents of the silo or crib.

A further object of this invention is to provide a ventilator for silos, cribs, or the like, which interacts with other units to provide a tightly constructed, and efficient storage compartment with adequate ventilation and embodying great inherent strength.

A still further object of my invention is to provide a ventilator unit for silos, cribs, or the like that is versatile in its adaptation to various types and shapes of structures.

A still further object of this invention is to provide a ventilator unit for silos, cribs, or the like that is versatile in its adaptation to various types and shapes of structures.

A still further object of this invention is to provide a ventilator unit for silos, cribs, or the like that is extremely economical in manufacture, durable, and efficient in use.

These and other objects will be apparent to those skilled in the art.

My invention consists in the construction, arrangement, and combination of the various integral and component parts of the device, whereby the objects contemplated are attained as hereinafter more fully set forth, pointed out in my claims and illustrated in the accompanying drawing, in which:

Fig. 1 is a side elevational view of a portion of a silo, crib, or other storage bin with my ventilator units incorporated therein.

Fig. 2 is an enlarged front end view of my ventilator units when they are used alone and interlocked with each other.

Fig. 3 is an enlarged top view of one of my ventilator units imposed between two concrete slabs or staves.

Fig. 4 is an enlarged top plan view of an alternate type of structure of my ventilator unit where it is desired that the side walls be flush with the outside contours of the crib or other storage compartment.

Fig. 5 is an enlarged top elevational view of one of my ventilator units showing the method of providing a certain amount of resiliency in the wall portions of the ventilator unit.

Fig. 6 is an enlarged, cross-sectional view of portions of two of my ventilator units, showing the method of interlocking the same vertically.

when they are used in conjunction with each other and is taken on the line 6—6 of Fig. 2.

Heretofore, it has been the usual practice to either dispense with the major portion of ventilation in silos, cribs, or the like, or to use either concrete, having holes cut therethrough, or wooden staves spaced at intervals to obtain ventilation. Both of these methods are unsatisfactory in that they are not flexible and cannot be changed or altered to obtain the maximum efficiency for the accommodation of various types of materials, such as grains or stock feeds, contained within the silo or crib. Furthermore, dirt, snow, moisture, and other foreign accumulations could enter the horizontal slots, thereby destroying some of the products being stored within the compartment. Also these various types of cribs and silos were designed for but one type of grain or the like. This prevents the transfer of grain from one crib to another, or the interchangeability of storage compartments relative to the products contained therein. Furthermore, these structures have been costly and difficult to erect, thereby eliminating a ready market for such structures. I have overcome such difficulties as will be hereinafter set forth.

Referring to the drawing, I have used the numeral 10 to indicate a flat sheet member of metal or the like. This sheet member has formed, therein, a series of louvered openings 11 for permitting air to circulate through the metallic sheet member 10 to the inside of a crib or the like. The numeral 12 designates a side rail extending along one of the marginal edges 35 of the sheet member 10 and being bent forwardly on an arc, and thence rearwardly to form a concave sill or side wall as shown in Fig. 3 of the drawing. Similarly the numeral 13 indicates a side rail extending parallel to the side rail 12 and on the opposite marginal edge of the sheet member 10. This rail 13 is also formed from the sheet member 10, is bent forwardly and thence rearwardly on an arc, as shown in the drawing, for forming a convex sill or side wall.

45 This structure is very important, and it will here be noted that the outside or forward edge of each of the side rails, 12 and 13, are turned edges, thereby giving more resistance to this railing edge when a load is imposed on the rearward side of the ventilator, and will also aid in preventing the rusting or other disfigurement of these forward edges of the rails 12 and 13. It will also be noted, by reference to Fig. 5, that a gap can be left between the forwardly extending positions of the rails 12 and 13, and the

rearwardly extending positions, presenting a certain amount of resiliency to assure a tight fit between units when they are interlocked with each other.

It will be noted that the rail 12 is concave toward its outer side, while the rail 13 is convex toward its outer side, thus permitting the continuous interlocking of units in a horizontal direction. The size and number of louvered openings stamped in each of the sheet members 10, 10 is dependent upon the pre-determined amount of air necessary for exact circulation and ventilation of the product being stored with respect to its volume of the crib or silo. The slot formed under each of the louvers is narrow enough to prevent rodents from entering the completed crib, and will prevent the contents from falling there-through.

My unit thus far described, may be used successfully in conjunction with the ordinary type of concrete staves of rectangular shape, having one of their longer marginal edges rounded concavely and their opposite marginal edges formed convexly and in exact relation to my ventilator. These staves are generally longer than are my 25 ventilating units, and may be spaced so as to overlap for a substantial distance, as shown in Fig. 1 of the drawing. These concrete staves I have designated by the numeral 14, and the 30 complete silo, crib, or like is built up of alternate overlapping sections of concrete staves, and any of my ventilator units, and if the structure being constructed is a silo, the ordinary bands 15 are placed about the structure and tightened. By 35 having the concrete staves 14 of longer dimensions than my ventilating units, the tightening bands 15 touch only the concrete portion of the silo, providing a rigid and substantial structure. It will also be noted, by reference to Fig. 4, that the sheet member 10 may be in a plane substantially even with the outside of the ventilator unit, and the side rails, 12 and 13, bent and formed so that the plates 10 will be flush with the outside surface of the crib or like structure. This feature is desirable in some instances and when certain types of structures are erected using 40 my ventilator unit.

When it is desired to construct a crib, silo, or the like from successive sections or entirely of my ventilator units, they may be interlocked in the manner shown in Figs. 2 and 6 of the drawing. The flat portion of the sheet member 10 has formed thereon, a shoulder 16 extending downwardly beyond the lower marginal confines of the rails 12 and 13. A plate 17 is then spot-welded, or otherwise secured to the rearward surface of the sheet member 10, thereby forming a receiving groove, capable of receiving the upper or opposite marginal edge of the next succeeding lower section or ventilator. By this structure the ventilators are locked together, and by placing the successive ventilator units at either side of the base units, a rigid assembly is obtained. The next succeeding plate or ventilator to the side may be spot welded to its previous plate, may be bolted thereto, or in the case of silos, may be held by the ordinary tightening plates, bands or the like.

In practical use, as many of my ventilator units as is deemed necessary for the proper ventilation of the structure, may be interspersed with concrete or like staves, or the entire assembled structure may be made up of interlocking units

of my ventilator. Due to the convex and concave sidewall portions of my ventilator, it is adaptable to any shape or contour, and may be used in rectangular structures, round structures, octagonal structures, and in fact, any shape or size of structure that may be desired. Also it is obviously easy to extend the size; either vertically or horizontally by the use of additional units.

Obviously if a silo or a crib is made up of my units, and it is desired, at times, to store small grain such as shelled corn, oats, wheat, or the like within the crib, the louvered slots may be closed. It will be noted that I have extended my louvers outwardly, providing a flat portion at the rear, over which may be placed building paper, a sheet of metallic material, or the like when using a crib constructed of my ventilating units for the storage of small grain or the like not needing ventilation.

Thus, it will be seen that I have provided a ventilator for silos, cribs, or the like, which fulfills all of my objects as extremely economical to manufacture and to assemble into a completed structure, is versatile in its adaptation to varying structures and to suitable conditions, which provides adequate ventilation, and which may be used in conjunction with any structure as an additional means of ventilation for the inside of the structure.

The side rail portions 12 and 13 may be herein-after referred to as side rail portions, interlocking means or flanges.

Some changes may be made in the construction, and arrangement of my improved ventilator for silos, cribs, or the like without departing from the real spirit and purpose of my invention, and it is my intention to cover by my claims any modified forms of structure or use of mechanical equivalents which may be reasonably included within their scope.

I claim:

1. In a device of the class described, a metallic sheet member having openings therein, a rail member formed along one of the marginal edges of said sheet member; said rail member extending first forwardly and then rearwardly on an arc to form a convex side rail, and a second side rail formed on the marginal edge of said sheet member opposite from and parallel to said first mentioned rail; said second mentioned rail being formed by bending said sheet member first forwardly and thence rearwardly to form a concave side rail.

2. In a device of the class described, a sheet member having louvered openings therein, a convex side rail formed along one of the marginal edges of said flat sheet member; said convex side rail being formed by bending said flat sheet member forwardly and inwardly and thence rearwardly in spaced relationship to said forwardly and inwardly extending portion for providing resiliency in said convex side rail, and a concave side rail formed on the opposite marginal edge of said flat sheet member parallel to said convex side rail; said concave side rail being formed by bending said flat sheet member forwardly and outwardly and thence rearwardly on an arc in spaced relationship to said forwardly and outwardly extending portion for providing resiliency in said concave side rail.

FRANK H. ANDERSON.
